UNITED STATES PATENT OFFICE.

DAVID C. BATTEY, OF FLORENCE, KANSAS.

WATER OR LIQUID ELEVATOR.

SPECIFICATION forming part of Letters Patent No. 397,889, dated February 19, 1889.

Application filed August 13, 1888. Serial No. 282,591. (No model.)

To all whom it may concern:

Be it known that I, DAVID C. BATTEY, a citizen of the United States, residing at Florence, in the county of Marion and State of Kansas, 5 have invented new and useful Improvements in Water or Liquid Elevators, of which the following is a specification.

My invention relates to improvements in water or liquid elevators; and it consists in a 10 certain novel construction and combination of devices, fully set forth hereinafter in connection with the accompanying drawings, and specifically pointed out in the appended claims.

15 In the drawings, Figure 1 is a vertical central sectional view of an elevator embodying my improvements. Fig. 2 is a similar view of the air-compressor, taken on the line xx of Fig. 1. Fig. 3 is a horizontal sectional view 20 of the compressor on the line yy of Fig. 2. Fig. 4 is a detail view of the trip-lever.

The object of this invention is to provide 25 means whereby the power of the ordinary water-service may be utilized to elevate cistern-water to a suitable tank in a building, to pump waste water out of cellars, &c., and to elevate liquids in breweries, distilleries, refineries, &c., and to accomplish this I employ the said power to compress air as follows:

30 A represents the compressing-cylinder, in which operates an inverted-cup-shaped plunger or float, B, and C and D represent, respectively, inlet and discharge pipes which communicate with the cylinder near its bottom. The ends of these pipes which project 35 into the cylinder are provided, respectively, with the stop-cocks or valves c and d , having the crank-arms c' and d' , whereby they may be operated. These crank-arms are connected 40 by the links e to the opposite ends of the operating-lever E, which is pivoted at its center to a suitable standard or support, F, on the bottom of the cylinder, and G represents an extensible shaft, which consists of the telescoping sections g and g' . The section g is secured rigidly at its lower end to the bottom 45 of the cylinder, and the movable section g' is tubular in form and slides on the lower section.

50 A swinging arm, II, having a weight, I, on its free end, is pivoted to the standard or support F in such a position that the weight nor-

mally rests on one arm of the lever E. If the weight rests on the arm h , (which is connected to the crank-arm c'), the stop-cock or valve c 55 is closed, and when the weight rests on the arm h' (which is connected to the crank-arm d') the stop-cock or valve d is closed.

K represent a trip-lever, which is mounted on the standard or support F, and is connected 60 at its free end to the upper section of the extension-shaft by means of the rod L. This lever is angular in shape, having the arms k k' , whereby, as the shaft G approaches the limit of its extension, the arm k engages the 65 weight and throws it over on the other side, and as the said shaft approaches the limit of its contraction the arm k' engages the weight and returns it to its first position. The upper end of the extension-shaft is connected 70 by the chains or flexible connections N to the center of the plunger or float B, and a socket, n, in the center of the plunger or float is adapted to bear on the upper end of the said shaft. When in its lowered position, the 75 plunger or float is supported by the vertical bars or supports O O.

P represents the receiving-cylinder of the elevator, which is connected to the top of the cylinder A by the pipe Q, and R represents a 80 pipe which communicates with the top of the receiving-cylinder, and is adapted to be submerged at its lower end in the water or liquid to be elevated. A vertical conducting-pipe extends nearly to the bottom of the receiving- 85 cylinder, and is adapted to communicate at its upper end with the reservoir or tank which is to contain the elevated water or liquid. The pipes R and S are provided at convenient points with upwardly-opening 90 valves r and s , respectively.

The operation of the improved elevator is as follows: The water is introduced through the inlet-pipe C, (which is connected to the service-pipe,) and the plunger or float is 95 thereby raised in the compressing-cylinder, and when the said plunger or float approaches the limit of its upward movement the arm k engages the weight I and carries it beyond the perpendicular, whereupon it drops upon the arm h of the operating-lever, thereby closing the valve c and opening the valve d . The water is discharged through the pipe D, and the plunger or float descends (thereby

creating a partial vacuum in the upper end of the compressing-cylinder and the connecting-pipe Q) until the plunger or float bears on the upper end of the extensible shaft, 5 when the latter will be contracted, the trip-lever will be operated, and its arm k' will engage the weight and carry it beyond the perpendicular, whereupon it will drop on the arm h', and the valve c will be opened and 10 the valve d closed. When the plunger or float ascends, the air in the upper portion of the compressing-cylinder, the connecting-pipe Q, and the receiving-cylinder is compressing, and this additional pressure on the 15 water in the receiving-cylinder forces the latter upward through the pipe S, (the valve s therein opening to allow it to pass,) and when the plunger or float descends a partial vacuum is created in the cylinders and the connecting-pipe, and the water is drawn into the receiving-cylinder through the pipe R. When 20 the plunger or float ascends, the valve r is closed and the valve s is opened, and when the plunger or float descends the valve r is 25 opened and the valve s is closed. In depressing the extensible shaft to cut off the inflow of water and open the discharge-pipe the weight of the plunger or float will be aided by the suction created by removing the water 30 from the under concave side of the said plunger or float, and thereby all necessary power will be obtained to properly operate the levers and the weight, as above described.

It will be evident that after the flow of water 35 through the inlet-pipe has been started the operation of the elevator is automatic and continuous, and the elevation of the liquid will be accomplished.

It will be found of advantage in constructing 40 this machine to make the discharge-pipe D longer than the pipe R, whereby the siphon action will aid in drawing the water into the receiving-cylinder.

Having described my invention, I claim—
45 1. The combination, with the cylinder having the inlet and discharge pipes C D, provided with valves c d, of the operating-lever connected at its opposite ends to the said valves c d, the weighted arm adapted to bear 50 on either arm of the said lever, the trip-lever adapted to throw the said weight from one arm of the operating-lever to the other, and the plunger or float connected to the said trip-lever, substantially as specified.

55 2. The combination, with the compressing-cylinder provided with inlet and outlet pipes C D, having valves c d, and the plunger or float operating in the cylinder, of the operating-lever pivoted at its center and connected 60 at its ends to the said valves, the swinging

arm H, provided with a weight, I, adapted to bear on either arm of the operating-lever, and the trip-lever K, connected to the plunger or float and provided with the arms k k', adapted to alternately engage the weight as 65 the plunger or float ascends and descends, to throw the same from one arm of the operating-lever to the other, substantially as and for the purpose specified.

3. The combination, with a cylinder provided with inlet and outlet pipes C D, having valves c d, and the plunger or float operating in the cylinder, of the operating-lever E, connected at its ends to the said valves, the weighted arm H, adapted to bear alternately 70 on the arms of the said lever, the extensible shaft G, connected at its upper end to the plunger or float, and the trip-lever connected to the extensible shaft and adapted to engage the weighted arm to change its position, substantially as specified. 75

4. The combination, with the cylinder provided with the pipes C D, having valves c d, of the operating-lever E, connected to the said valves, the arm H, provided with a weight, I, 80 adapted to bear alternately on the arms of the lever E, the extensible shaft G, the trip-lever connected to the said shaft and adapted to engage to change its position from one arm of the lever to the other, the weighted arm, 85 and the plunger or float B, connected to the upper end of the extensible shaft by means of a chain or flexible connection, H, and provided with a socket, n, to bear on the upper end of said shaft, substantially as specified. 90

5. The cylinder provided with the inlet and outlet pipes C D, having valves c d, the operating-lever E, connected to the said valves, the weighted arm H, adapted to operate the said lever, the extensible shaft G, and the trip-lever connected to the said shaft and adapted to operate the weighted arm, in combination with the inverted-cup-shaped plunger or float B, operating snugly in the cylinder and connected to the upper end of the extensible shaft 100 by a chain or other flexible connection, the central socket, n, adapted to bear on the upper end of the extensible shaft, and the vertical bars or supports O O, arranged within the cylinder and adapted to limit the downward movement of the plunger, substantially 105 as specified. 110

In testimony that I claim the foregoing as my own I have hereto affixed my signature in presence of two witnesses.

DAVID C. BATTEY.
